UNITED STATES PATENT OFFICE.

HENRY M. SHEER, OF QUINCY, ILLINOIS, ASSIGNEE TO H. M. SHEER COMPANY, OF QUINCY, ILLINOIS, A CORPORATION OF ILLINOIS.

COMBINED HEATING DRUM AND CANOPY.

Application filed February 19, 1923. Serial No. 620,112.

My invention relates to an improvement in combined heating drums and canopies for brooders.

The object of the present invention is to 5 provide a canopy for brooders which is both simple and inexpensive, and this is accomplished by providing a heating drum which receives and carries off the products of combustion and which suspends in an adjustable position, the wings forming the canopy.

In the accompanying drawings:

Figure 1 is an elevation partly in vertical section;

Figure 2 is a bottom plan view;

15 Figure 3 is a detail showing a form of diaphragm in perspective;

Fig. 4 is a perspective view of one of the wings detached; and

20 Fig. 5 is a detail perspective view of one of the braces.

A represents a drum or radiator preferably made of sheet metal and mounted on a hollow cylindrical pedestal 1 to which it may be permanently or detachably secured 25 at the joint 2. A diaphragm 3 is removably supported within the drum and has down-turned sides 4 forming supports therefor. The corners of this diaphragm 3 may be cut off to form outlets 5 for the products 30 of combustion which rise from the burner 6 and spread beneath the diaphragm 3 and issue through the outlets 5 at the corners into the chamber 7 of the drum, and finally through the central pipe or chimney 8.

35 The top plate 9 of the drum is preferably bent upwardly and outwardly forming an inverted L-shaped flange 10 which fits and rests removably upon the upper edge of the drum.

40 The canopy is preferably made of several wing sections 11 of which four are shown in the drawings. These are provided with flanges 12 at the upper edge as one of several simple means for removably supporting the canopy sections or wings upon the upper edge of the drum and also to give strength to the sections or wings of the canopy, and a flange 13 at the lower edge also gives strength and rigidity to these 45 canopy sections or wings.

The wings may be adjustably supported in any approved manner, as for instance, by braces 14, which will admit of their being raised or lowered by securing their inner

ends at different points on the sides of the 55 drum, as indicated at 18.

Air to support combustion is supplied through the holes 15 in the hollow cylindrical pedestal 1. When an oil burner is used the oil is supplied from the tank 16, 60 and the pipe 17 which leads from the tank to the burner. As illustrated in the drawings, the hollow pedestal 1 has a double function. It not only supports the drum or radiator, but also encloses the burner and 65 protects the chicks therefrom.

While the drum and canopy is shown in the form of a square, obviously it might be circular or octagonal or of other forms. Other means of detachably supporting the canopy wings might also be employed as 70 well as different means of bracing them and the device is applicable to air blast stoves, as well as oil burner heaters, it being complete as an article by itself without departing 75 from the spirit and scope of my invention.

It is also understood that the height of both the drum or radiator and the wings 80 from the ground is a mere matter of detail.

From the foregoing, it will be seen that provision is made for protecting and keeping the young chicks warm and sheltered in a more or less even temperature without 85 endangering their lives by coming in contact with the burner, or by reason of their having to breathe any of the products of combustion from which they are always 90 protected.

I claim:

1. The combination of a drum, wings having hooks at the upper edges thereof for being detachably hooked over the edges of the drum, and means secured to the wings 95 for engaging the sides of the drum and supporting the wings in a predetermined spaced relation therefrom.

2. The combination of a drum, wings adjustably connected therewith and having longitudinal slots formed therein, braces extending from the wings to the drum for adjustably supporting the wings, and means extending through the slots and engaging the braces for adjusting said braces relative to the wings. 100

3. The combination of a drum, wings detachably connected therewith and having 105

longitudinal slots formed therein, braces extending from the wings and engaging the sides of the drum for adjustably supporting the wings, and means extending through the slots and braces for adjustably securing said braces to the wings.

4. The combination of a drum, a removable top therefor having a substantially U

shaped outer edge hooked over the upper edge of the drum, and wings having hooked flanges at the upper edges thereof for supporting said wings from the edges of the top of the drum. 10

In testimony whereof I affix my signature.

HENRY M. SHEER.
